APPARATUS FOR INDIVIDUALIZING COTTONSEED

Leo L. Holzenthal, New Orleans, Edward A. Gastrock, Metairie, and William T. Gentry, Jr., New Orleans, La., assignors to the United States of America as represented by the Secretary of Agriculture

Filed Sept. 18, 1962, Ser. No. 224,934

3 Claims. (Cl. 19—65)

(Granted under Title 35, U.S. Code (1952), sec. 266)

A non-exclusive, irrevocable, royalty-free license in the invention herein described, throughout the world for all purposes of the United States Government, with the power to grant sublicenses for such purposes, is hereby granted to the Government of the United States of America.

This invention relates to an apparatus for individualizing cottonseed and feeding the individualized cottonseed to a cleaning device that will subsequently separate the cottonseed from debris such as field trash, cottonseed stems, leaves, outer boll wall, shale, sand, dirt, and the like. Such debris is commonly associated with cottonseed in the matted and tangled condition. The operation of individualizing or particularizing cottonseed is referred to in the industry as the "opening" of cottonseed, and these terms will be used throughout the specification and claims to refer to such operations. It is well known that the efficient cleaning of cottonseed by whatever means requires the thorough opening of the matted and compacted mass of cottonseed as it comes from the gin.

The apparatus that is the subject of this invention is designed as a piece of auxiliary equipment operating as an adjunct to a cottonseed cleaning device. The opening and the feeding of the opened cottonseed to a cottonseed cleaning apparatus such as the one described in U.S. 2,964,180, is a function to which the apparatus of this invention is particularly well suited. In general, as seen in the drawings, which are described in detail below, the apparatus according to this invention comprises a contoured housing having an inlet and an outlet end, or delivery opening, and a pair of adjacent rotors mounted in the housing with their axes of rotation parallel to each other. Each rotor is provided with a plurality of radially-extending spikes. Before the inlet end, and communicating therewith, is a first box-like chamber having parallel side walls, while to the delivery opening, and communicating therewith, there is attached a second box-like chamber with at least two facing side walls uniformly flaring outward relative to one another in a direction away from the contoured housing. A slanted rebound baffle is attached to the expansion chamber opposite the point where the latter is attached to the outlet end of the contoured housing and forms another wall of the expansion chamber. This baffle is disposed at an angle away from and outward relative to the plane of rotation of the rotors. In the preferred arrangement, the contoured housing is provided with the feed opening at the top, immediately above the rotors, while the delivery opening is immediately below the rotors. The expansion chamber attached to the delivery opening therefore extends downward from the point of attachment with its walls flaring outward laterally in a horizontal direction. It is the purpose of this expansion compartment to accommodate the increased space required by the opened cottonseed after their passage through the spiked rotors. The rebound baffle, which is transverse to the expansion chamber, slopes downward from the rear wall of the latter to the front, and is so located relative to the spiked rotors that the entire volume of individualized cottonseed issuing from the rotors following passage through the rotors, is delivered onto the sloped surface of the

2

rebound baffle board and directed outward from the sloped surface toward the adjacent cottonseed cleaning device. A covering of rubber or similar elastic material is provided over the baffle. The rebound baffle board feature of the instant apparatus functions to effect the efficient removal of debris from the opened cottonseed and effectively prevents the retangling and matting of the opened cottonseed prior to their entry into the adjacent cottonseed cleaning device. The spikes of the rotors of this apparatus are mounted in rows as radii of the rotor shafts and the spikes are covered with rubber or some material with similar properties for the purpose of preventing fragmentation of the cottonseed during passage through the rotors. Rotor rotation is counter each to the other and counter severally to the flow direction of the cottonseed entering the feed opening of the rotor housing. The speed of rotation is adjustable to suit the feed rate and the difficulty of the opening job. We prefer to operate our rotors, which are approximately 9" in diameter, at 950 r.p.m., which speed affords the efficient opening of cottonseed at the rate of about one ton per hour.

So that the invention will be better understood, reference is now made to the following detailed description of the preferred form of the apparatus and to the accompanying drawings in which:

FIGURE 1 is a front elevation of the apparatus, with parts omitted (e.g., gears 30 and 31) for clarity, showing the arrangement of the rotors with respect to the inlet and discharge ends;

FIGURE 2 is a side elevation in section taken on line 2—2 in FIGURE 1;

FIGURE 3 is a plan view of the apparatus, with a portion of the upper structure removed to show the relative arrangement of the spiked rotors; and

FIGURE 4 is an enlarged view of one of the rotor spikes showing the resilient covering.

Referring to FIGURES 1 and 2, it is seen that the apparatus comprises a pair of curved side walls 1 and 2 and rectilinear front and rear walls 3 and 4, respectively. The combination of side walls 1 and 2 and front and rear walls 3 and 4 constitutes the contoured housing, indicated generally by 5, previously referred to. The contoured housing may be assembled in any suitable manner known to skilled mechanics. Thus, as can be seen from FIGURES 1-3, front and rear walls 3 and 4 can be provided with flanges 34, 35, 36, and 37 which match the curvature of, but extend beyond side walls 1 and 2. The latter can be provided with a plurality of lugs or brackets (not shown) secured thereto and fastened to front and rear walls 3 and 4 by means of bolts 38 and nuts 39. The upper ends of the curved side walls lie in a horizontal plane which defines the inlet end 6 of the contoured housing. Extending upward from the upper ends of the curved side walls are a pair of parallel rectilinear side walls 7 and 8, which, together with rectilinear front and rear walls 3 and 4, constitute a first box-like compartment 9. Side walls 7 and 8 may be integral with their respective curved walls or they may be separate elements secured in any suitable manner to the curved side walls. Mounted on top of compartment 9 is a funnel member 10, having a restricted feed opening, through which clumps of matted cottonseed are fed to the apparatus.

The lower ends of the curved side walls lie in a plane defining an outlet end, or discharge opening 11 of the contoured housing. Connected to the lower ends of the curved side walls is a pair of downwardly extending, outwardly flaring rectilinear side walls 12 and 13, which together with the lower extension 14 of rear wall 4, form an expansion chamber 15, immediately below and communicating with discharge opening 11. The front of the apparatus is provided with a sloping partial front

wall 16, while, at the lowermost end, a forwardly slanted baffle 17 is attached to side walls 12 and 13 and rear wall 14 to form a bottom for the expansion chamber.

Inside the contoured housing is a pair of rotors, generally designated as 18 and 19, having their axes of rotation parallel, and journaled in bearings 20, 21, 22, and 23 secured to front and rear walls 3 and 4. As will be apparent from FIGURE 2, baffle 17 is disposed at an angle away from and outward relative to the plane of rotation of rotors 18 and 19. The rotors comprise shaft portions 24 and 25 upon which are rigidly mounted a plurality of radially extending spikes 26 having a cover 27 of rubber or any other suitable resilient material. Details of one of such spikes and its cover are shown enlarged in FIGURE 4. As can be seen from FIGURE 3, the spikes on one rotor are not vis-a-vis the spikes on the other rotor, but are staggered with respect to one another. Shafts 24 and 25 are provided with shaft extensions 28 and 29 extending through rear wall 4 to provide a mounting for meshing driving gears 30 and 31. Shaft extension 29 is further provided with pulley 32 which is connected by means of a belt, not shown, to any suitable driving means, also not shown. In this manner, rotors 18 and 19 are made to rotate in opposite directions, as shown by the curved arrows in FIGURE 1.

In the preferred form of the apparatus, sides 12 and 13, back 14, and baffle 17 are each provided with a rubber or other resilient cover 33 to protect their surfaces and to provide a resilient rebound surface which prevents fracture of the cottonseed and also improves the rebound characteristics of the latter.

Although the relative spatial positions of the rotors, spikes, and walls of the contoured housing have been shown somewhat exaggerated to facilitate illustration, the distances are actually such that clumps of unopened cottonseed are unable to pass either between the spikes or between the two rotors themselves, or between the rotors and the curved sides of the contoured housing. However, the spacing is great enough so that individualized or opened cottonseed are able to pass freely between the rotors and the curved sides of the housing.

The operation of the opening and feeding device can be described as follows. Unopened cottonseed is fed down through the feed orifice 10 into the untangling compartment 9 located immediately above the contoured rotor housing and communicating therewith. The unopened and tangled masses of cottonseed contact the rapidly moving spikes 26 of the counter rotating rotors and conglomerates of unopened cottonseed are struck by the rapidly moving spikes and driven back upward toward the feed orifice. Note that the constricted feed orifice 10 performs the essential function of preventing cottonseed that is inside the machine, and undergoing the process of individualization, from being driven up and out of the rotor compartment and the disentangling compartment. Although clumps of unopened cottonseed are unable to pass either between the two rotors or around the rotors alongside the contoured housing, individualized cottonseed are able to pass freely around the rotors alongside the inner wall of the contoured rotor housing in a path indicated by arrows. Unopened clumps of cottonseed are continually acted upon by the revolving spiked rotors which causes the clumps to move in a rolling, circular path in the untangling compartment 9 immediately above the rotors, as indicated in

FIGURE 1 by the circles of arrows above rotors 18 and 19, until such time as they become individualized. The individualized cottonseed which pass the rotors and are accelerated to a relatively high velocity by the rotors are driven first against the downward and outward flaring sidewalls 12 and 13 of the expansion chamber 15, and then onto the sloping face of the rebound baffle board 17. The now thoroughly untangled cottonseed are deflected from the rebound baffle board out and away from the opening apparatus toward a cottonseed cleaning device such as, for example, the inclined travelling belt cleaner described in U.S. 2,964,180.

Although front and rear walls 3 and 4, as well as partial wall 16, have been shown in the drawings as being transparent, it will be obvious to those skilled in the art that this property is not essential to practicing the invention and that these wall members can be made of any suitable structural material without in the least affecting the operation of the apparatus.

Having thus described the opening and cleaning apparatus for cottonseed, what we claim is:

1. Apparatus for particularizing cottonseed comprising:
  - (a) a contoured housing having an inlet and an outlet end;
  - (b) a pair of adjacent rotors mounted in the contoured housing with their axes of rotation parallel;
  - (c) a plurality of radially-extending spikes secured to each rotor;
  - (d) means connected to the rotors for driving said rotors;
  - (e) a first combination of rectilinear side walls defining a first essentially box-like compartment with parallel facing side walls contiguous with and in communication with the inlet end of the contoured housing, said first box-like compartment being provided with a restricted feed orifice;
  - (f) a second combination of rectilinear walls defining a second essentially box-like compartment attached to and in communication with the outlet end of the contoured housing, said second box-like compartment forming an expansion chamber having at least two opposite side walls uniformly flared outward relative to one another in a direction away from the point of attachment to the contoured housing; and
  - (g) a slanted rebound baffle attached to the second box-like compartment opposite the point of attachment of said second box-like compartment to the contoured housing and forming another rectilinear wall of said second box-like compartment, said baffle being disposed at an angle away from and outward relative to the plane of rotation of the rotors.
2. The apparatus of claim 1 wherein the individual rotor spikes are encased in an elastic material.
3. The apparatus of claim 1 wherein the inner walls of the said second box-like compartment and the inner surface of the rebound baffle board are covered with a layer of smooth, resilient material.
